(57) **CLAIM**

The ornamental design for a combined climbing components for children, as shown and described.

DESCRIPTION

FIG. 1 is a perspective view of the combined climbing components for children, showing my new design;

FIG. 2 is a perspective view thereof, the components arranged in an alternate configuration;
FIG. 3 is a perspective view thereof, the components arranged in a third alternate configuration;
FIG. 4 is a perspective view thereof, the components arranged in a fourth alternate configuration;
FIG. 5 is a perspective view thereof, the components arranged in a fifth alternate configuration;
FIG. 6 is a top perspective view of one component, shown separately for completeness;
FIG. 7 is a bottom perspective view of FIG. 6;
FIG. 8 is a front elevational view of FIG. 7, the undisclosed rear elevation being a mirror image;
FIG. 9 is a left side view of FIG. 7;
FIG. 10 is a right side view of FIG. 7;
FIG. 11 is a top plan view of FIG. 7;
FIG. 12 is a bottom plan view of FIG. 7;
FIG. 13 is a top perspective view of a second component, shown separately for completeness;
FIG. 14 is a bottom perspective view of FIG. 13;
FIG. 15 is a front elevational view of FIG. 13, the undisclosed rear elevation being a mirror image;
FIG. 16 is a left side view of FIG. 13;
FIG. 17 is a right side view of FIG. 13;
FIG. 18 is a top plan view of FIG. 13;
FIG. 19 is a bottom plan view of FIG. 13;
FIG. 20 is a top perspective view of a third component, shown separately for completeness;
FIG. 21 is a bottom perspective view of FIG. 20;
FIG. 22 is a front elevational view of FIG. 20, the undisclosed rear elevation being a mirror image;
FIG. 23 is a left side view of FIG. 20;
FIG. 24 is a right side view of FIG. 20;
FIG. 25 is a top plan view of FIG. 20;
FIG. 26 is a bottom plan view of FIG. 20;
FIG. 27 is a top perspective view of a fourth component, shown separately for completeness;
FIG. 28 is a bottom perspective view of FIG. 27;
FIG. 29 is a front elevational view of FIG. 27, the undisclosed rear elevation being a mirror image;
FIG. 30 is a left side view of FIG. 27;
FIG. 31 is a right side view of FIG. 27;
FIG. 32 is a top plan view of FIG. 27;
FIG. 33 is a bottom plan view of FIG. 27;

(Continued)

FIG. 34 is a top perspective view of a fifth component, shown separately for completeness;
 FIG. 35 is a bottom perspective view of FIG. 34;
 FIG. 36 is a front elevational view of FIG. 34; the undisclosed rear elevation being a mirror image;
 FIG. 37 is a left side view of FIG. 34;
 FIG. 38 is a right side view of FIG. 34;
 FIG. 39 is a top plan view of FIG. 34; and,
 FIG. 40 is a bottom plan view of FIG. 34.
